UNITED STATES PATENT OFFICE.

HOMER HELM, OF OAKLAND, CALIFORNIA, ASSIGNOR OF ONE-HALF TO EDNA HELM,
OF OAKLAND, CALIFORNIA.

WRIST SIGNAL.

Application filed February 3, 1923. Serial No. 616,687.

To all whom it may concern:

Be it known that I, HOMER HELM, a citizen of the United States, residing at Oakland, in the county of Alameda and State of California, have invented a new and useful Wrist Signal, of which the following is a specification.

This invention relates to improvements in signals, and more especially to a signal designed for attachment to the wrist, and for the use of vehicle drivers, traffic officers and others giving motion or direction signals.

The object of the invention is to produce a signal that may be carried on the wrist of the user; also one that may be exhibited and rendered visible both from the front and rear when the user extends his arm, but will be covered at other times by the user's sleeve. A further object is to produce the signal as a new article of manufacture, having adjusting attaching means to accommodate the various sizes of wrists.

In carrying out my invention I make a bracelet of any suitable material, such as leather, and attach to it two crystals or brilliants adapted to emanate red or other suitably colored rays of light, positioning the crystals on the bracelet so that when the device is worn, the crystals will be on opposite sides of the wearer's wrist and rendered visible by the reflection of extraneous light.

The accompanying sheet of drawings forming a part of this specification illustrates an embodiment of my invention, and what I claim as new, is particularly pointed out in the appended claim following the specification.

Figure 1 of the drawings, is an elevation from the rear, showing a portion of an automobile and with an arm extended, the back of the hand being towards the observer and with my invention applied to the wrist and showing one of the brilliants.

Figure 2 is a plan of Figure 1, showing the relative position of both brilliants when in use, and adapted to be viewed from both front and rear.

Figure 3 is an expanded view of a wrist band, showing both brilliants and their relative positions thereon, and showing also a fastening means for the ends of the band.

Figure 4 is a view showing a means of securing a brilliant to the band, the latter being in section and the brilliant in elevation.

Referring to the drawing and the figures

thereof:—The reference numeral 1 represents the back of an automobile and 2 the top thereof, and 3 a hand and arm extended laterally therefrom, to give, in this instance a direction signal. When the arm is extended, the sleeve 4 naturally draws back, as shown, exposing the wrist 5 and signal 6 to view.

The signal comprises a wrist band 7, upon which are mounted the brilliants 8. The method of attaching the brilliants to the band is immaterial, but I have shown a very effective method, to wit; the brilliant is set in a base support 9, having at its back a stud 10 and a head 11, and interposed therebetween a disc 12. These members extend through the outer ply of the band 13 and are covered by the inner ply 14 thereof, which latter protects the wrist.

The brilliant 8 is preferably of ruby-tinted glass having many facets and silvered on its back, or it may be of clear glass provided with a colored background 15. The latter may be a colored disc interposed between the crystal and base 9, or the base may be made a reflecting surface and colored.

In Figure 3 I have shown a convenient fastening for the ends of a belt-form of wrist band, the said fastening comprising a series of ordinary snap-buttons, such as 16 glove buttons 16 sewed thereon at one end and a single accompanying half 17 sewed at the other end.

In operation, as when driving an automobile, the driver when desiring to signal extends his arm and the wrist bracelet at once becomes visible and an observer to the rear or in front of the vehicle notes in addition to the hand, well defined reflected light rays of red which accentuate the signal given. At night, the brilliants of my signal render additional and very efficient service, as the contrast with the hand is very marked, the brilliants receiving their light from the head-lights of approaching vehicles and from other sources.

When one leaves his car for a little while, he does not have to remove the signal from his wrist, because the coat sleeve normally covers it.

I claim:—

A traffic signal comprising a relatively long band compared to its width, said band being plain and smooth on one side and adapted to encircle the wrist, the ends of the

2
band being reduced in width rounded and similarly shaped and having button adjusting means on the ends on the side opposite the smooth side adapted for engagement with various size wrists, and said band having intermediate the ends and on the button side a pair of spaced crystals such that when

the band is secured to a wrist the crystals will be opposed and on opposite sides of the wrist, the signal being adapted to be worn ¹⁰ on either wrist irrespective of end-for-end placement about the wrist.

In testimony whereof I affix my signature.
HOMER HELM.
